THERMOMETER

Donald O. North, Menlo Park, Calif.

Application July 13, 1956, Serial No. 42,243

Term of patent 3½ years

(Cl. D52—7)

FIG. 1

FIG. 2

FIG. 3

Fig. 1 is a perspective view of a thermometer, showing my new design,

Fig. 2 is a side view of the thermometer, and
Fig. 3 is a front view of the thermometer.

The rear of the thermometer is substantially the same in appearance as the front, except for the recessed dial portion.

I claim:

The ornamental design for a thermometer, as shown and described.
